SWIMMING LURE BODY

William O. Roberts, 421 Laurel St., Apt. #29, Lufkin, Tex. 75901, and Robert Glynn Carver, P.O. Box 598, Minden, La. 71055

Filed Feb. 16, 1974, Ser. No. 442,349

Term of patent 14 years

Int. Cl. D22—05

U.S. Cl. D22—27

Fig. 1.

Fig. 2.

Fig. 3.

Fig. 4.

Fig. 5.

FIG. 1 is a perspective view of a swimming lure body embodying my new design.

FIG. 2 is a side elevational view of the lure body, the side not shown being a mirror image of the side shown.

FIG. 3 is a top view thereof.

FIG. 4 is a rear end view thereof.

FIG. 5 is a front end view thereof.

I claim:

The ornamental design for a swimming lure body, substantially as shown and described.
